LOLLIPOP

William B. Lupton, Portland, Oreg.

Application September 29, 1948, Serial No. 148,808

Term of patent 14 years

(Cl. D82—2)

To all whom it may concern:

Be it hereby known that I, William B. Lupton, a citizen of the United States, residing at Portland, in the county of Multnomah and State of Oregon, have invented a new, original, and ornamental Design for a Lollipop, of which the following is a specification, reference being had to the accompanying drawing, forming a part thereof, in which

Fig. 1 is a front elevation of a lollipop, showing my new design.

Fig. 2 is a plan of Fig. 1.

Fig. 3 is a side elevation of Fig. 1.

I claim:

The ornamental design for a lollipop, as shown.

WILLIAM B. LUPTON.
